UNITED STATES PATENT OFFICE.

BENJAMIN SHEPARD SPAULDING, OF ARCATA, CALIFORNIA.

LOG TROLLEY.

Application filed October 3, 1921. Serial No. 505,021.

To all whom it may concern:

Be it known that I, BENJAMIN S. SPAULDING, a citizen of the United States, residing at Arcata, in the county of Humboldt and

5 State of California, have invented a new and useful Log Trolley, of which the following is a specification.

The device forming the subject matter of this invention is a trolley adapted to be 10 used for logging operations and the like, the device being so constructed that the same will maintain its grip upon the cableway whilst the log or other article is being drawn along the ground; the construction 15 being such that when the log is out of engagement with the ground, the trolley will move readily along the cableway.

This invention discloses a trolley operating after the manner of the structure shown 20 in my Patent No. 1,065,399, granted on June 24, 1913, and the present invention aims to accomplish the result contemplated in the patent above mentioned, through the instrumentality of a much simplified means.

25 It is within the province of the disclosure to improve generally and to enhance the utility of devices of that type to which the invention appertains.

With the above and other objects in view, 30 which will appear as the description proceeds, the invention resides in the combination and arrangement of parts and in the details of construction hereinafter described and claimed, it being understood that, within 35 the scope of what is claimed, changes in the precise embodiment of the invention shown can be made without departing from the spirit of the invention.

In the accompanying drawings:—

40 Figure 1 shows in longitudinal section, a device constructed in accordance with the invention, parts appearing in elevation; Figure 2 is a top plan, the line 1—1 in Figure 2 indicating the cutting plane on which 45 Figure 1 is taken; Figure 3 is a section on the line 3—3 of Figure 1.

The trolley forming the subject matter of this invention includes a pair of side members or plates 1 having openings 2, there 50 being seats 3 in the side members 1 at the lower edge of the openings 2. In the inner surfaces of the side members or plates 1, guide grooves 4 are fashioned. The plates 1 are connected adjacent to their lower corners by bolts or the like, indicated at 5, 55 spacers 6 being carried by the bolts, the

spacers being located between the side members or plates 1. Clevices 7 are mounted on the connecting devices 5 and serve as places of attachment for the outhaul and return 60 lines.

Shafts 8 are journaled in the upper corners of the plates 1, sheaves 11 being journaled on the shafts 8 and being located between the side members or plates 1. 65 Shafts 12 are mounted in the side plates 1, between the shafts 8 and are located at a level slightly above the line connecting the shafts 8. Sheaves 14 are located between the side members 1 and are journaled on the shafts 12. Shafts 15 are mounted in the side members or plates 1, adjacent to the lower edges of the side plates. The shafts 15 are located out of vertical alinement with the shafts 12 and 8. Sheaves 16 are journaled on the shafts 15 and are disposed between the side plates 1. All of the shafts hereinbefore enumerated, may be provided with bores 9, the outer ends of the shafts carrying oil cups 10 communicating with the 80 bores, the obvious function of the oil cups and the bores being to lubricate the various sheaves.

A slide 17 preferably in the form of a bar, is held for right line sliding movement in 85 the guide grooves 4. Intermediate its ends, the slide 17 is supplied with an opening 18. A pin or axle 19 is mounted in the slide 17 and extends across the opening 18. The ends of the pin or axle 19 are adapted to be 90 received in the seats 3, to hold the slide against movement longitudinally of the plates when in lowered position. A sheave 26 is located in the opening 18 of the slide 17 and is carried for rotation on the pin or 95 axle 19. In the lower end of the slide 17 there is a notch 20, across which extends a bolt 21. The upper ends of a clevic 22 are mounted on the bolt 21. A block 24 is supported on the lower portion of the clevic 22 and has a reduced upper end 23, received in the notch 20 which is fashioned in the lower end of the slide 17; the parts above enumerated coacting to steady the block 24. A pulley 25 is journaled in the block 24. 100 105

What is claimed is:—

1. In a device of the class described, a trolley, sheaves journaled in the upper portion of the trolley; a slide mounted for reciprocation in the trolley and located between the sheaves; a sheave carried by the slide; interengaging elements on the slide 110

and on the trolley, limiting the movement of the slide; and a pulley block carried by the slide.

2. In a device of the class described, a trolley; sheaves located in the upper and lower portions of the trolley; a slide carried by the trolley and mounted for right line reciprocation and located between the sheaves; means for limiting the reciprocation of the slide; a guiding means carried by

the lower end of the slide; and a sheave mounted on the slide.

In testimony that I claim the foregoing as my own, I have hereto affixed my signature in the presence of two witnesses.

BENJAMIN SHEPARD SPAULDING.
